UNITED STATES PATENT OFFICE.

JACOB B. STRUBLE, OF WILKINSBURG, PENNSYLVANIA, ASSIGNOR TO THE UNION SWITCH & SIGNAL COMPANY, OF SWISSVALL, PENNSYLVANIA, A CORPORATION OF PENNSYLVANIA.

ELECTRIC SIGNALING.

No. 849,171.

Specification of Letters Patent.

Patented April 2, 1907.

Application filed December 3, 1902. Renewed January 17, 1906. Serial No. 296,445.

To all whom it may concern:

Be it known that I, JACOB B. STRUBLE, residing at Wilkinsburg, in the county of Allegheny and State of Pennsylvania, a citizen 5 of the United States, have invented or discovered certain new and useful Improvements in Electric Signaling, of which the following is a specification.

In application filed December 3, 1902, Serial No. 123,711, I have described and claimed certain improvements in and relating to railway signaling involving the employment of alternating current in the track-circuits for the operation or control of the 15 signals and having for its object the controlling of a signal or signals of one section by a signal or signals of another section through a modification or change in one or more of the characteristics of the current in the 20 track-circuit.

The invention described herein has for its object a construction and combination of apparatus whereby a signal or signals of one section can be controlled in accordance with 25 the conditions on another section by effecting a displacement of the normal phase relation of the alternating signaling current in the track circuit.

The invention is hereinafter more fully described and claimed.

In the accompanying drawings, Figure 1 is a diagrammatic view of a portion of a railway-track, showing the block-sections unoccupied and the signals clear and embodying 35 my invention. Fig. 2 is a similar view showing one of the track-sections occupied and the signals indicating such condition, and Fig. 3 is a similar view illustrating a modified form of signal-controlling motor.

Similar reference characters designate 40 corresponding parts in all of the figures.

In the practice of my invention the line of rails 1, which is made electrically continuous, is connected to one pole of an alternating 45 generator 6, which has its other terminal connected to the feed-wire 7. The other line of rails is divided by suitable insulation into a series of sections 2, 3, &c., of suitable length.

Home and distant signals 4 and 5 on the 50 same post are arranged at the entrance ends of the sections and are adapted to be operated either directly by the currents in the track-circuit, as shown and described in the

application above referred to, or the operating mechanisms 17 and 18 of the signals are 55 included in independent circuits controlled through suitable mechanisms by the track-circuits. It is preferred when independent signal-operating circuits are employed that they should derive their currents from the 60 generator 6 by including the primary of a generator 6 by including the primary of a transformer 19 in the circuit of the generator 6 and the secondary of the transformer in the signal-operating circuits, as shown. These 65 signal-circuits contain make-and-break mechanisms consisting of contact-plates 32 and 33 and movable fingers 30 and 31, connected to movable members of motors operating as hereinafter described.

At each section the primary of a transformer A has its terminals connected, respectively, to the continuous rail 1 and the feed-wire 7. The secondary of the transformer has one terminal connected to the continuous line of rails 1, while the opposite 75 terminal is connected to one of a pair of contact-plates 11, the member being connected to one terminal of a reactance or phase-displacing coil 40, which has its other terminal connected to the rail-section 2. 80

The plates of the pair 11 are arranged so as to be electrically connected by the movable member 12 of the circuit-shifting mechanism, which is operated in accordance with the conditions existing on section 3 and 85 preferably by the home signal 4^a. This movable member 12 when shifted from the plates 11 will connect a pair of plates 10, one of which is connected to an intermediate terminal of the secondary 9 of the transformer and the other plate to the rail-section 2 in such a manner as to form a circuit 90 around the reactive coil 40. By changing the ratio of the transformer in the manner stated, which is similar to that described 95 and shown in the application referred to, the lowering of the power factor due to the phase displacement when reactance 40 is in circuit is compensated for. A resistance 13 is interposed in the track-circuit, so as 100 to prevent an excessive flow of current in the track when the latter is short-circuited by a train.

The translating device or motor B consists of cores or poles 24, having the coils 25 105 in series with the track-circuit of section 2

and a disk 29 pivotally mounted so as to be movable between the poles. The poles of the motor are slotted, forming sections, one of which on each pole is surrounded by a closed circuit 54. The motor is connected to the finger 30, controlling the circuit of home signal 4, and is so constructed and proportioned as to be operative by an alternating current either in or out of phase with the voltage (provided such displacement is not a quadrature) to shift the finger 30 into contact with plate 32 and clear the home signal 4 of section 2. Hence said signal will be held in clear position in either position of the movable member 12, provided no train is present on section 2. The translating device or motor C has one of its pole-pieces, as 41, surrounded by a coil 42 of comparatively few turns, said coil being in series with the coil 25 of motor B and responsive to current-wave. The other pole-piece 44 is surrounded by a coil 43 of relatively many turns and having its terminals connected across the track-circuit of section and responsive to pressure or voltage wave. This mechanism is similar to that found in the wattmeter and operates on the same principle. The movable member or disk 29^a of the motor is connected to the finger 31, controlling the circuit of distant signal 5. The motor is so designed that when the voltage and current on the track-circuit are in phase—i. e., when the movable member 12 connects the plates 10, the signal 4^a of section 3 being at "danger"—the disk 29^a will not be shifted and the circuit of distant signal 5 will be open and the signal at "caution;" but when the contact-plates 11 are connected by the movement of signal 4^a to clear the voltage and current in the track-circuit of section will be thrown out of phase and a shifting field produced in motor C, thereby causing such a movement of disk 29^a as to bring finger 31 in contact with plate 33, closing the circuit of signal 5, causing the same to go to clear position.

In order to prevent any disturbing influence due to reactance which the magnets having pole-pieces 24 and 41 with their coils may have on the phase relation in the circuit, so as to partially nullify the operation of the motor C, a condenser 45 may be employed.

In order to prevent the reactance or phase displacer 40 from producing a phase displacement in the main feed-wire 7, and thereby produce objectionable effects on other track-circuits signal mechanism supplied by the feed-wire, a condenser 46 may be placed in circuit with the primary or secondary of the transformer A or in circuit with both.

In lieu of using two controlling-motors, as shown in Figs. 1 and 2, and maintaining a uniform power factor in the track-circuit by changing the ratio of the transformer simul-

tafieous with a change of phase the construction and arrangement shown in Fig. 3 may be employed. As shown therein, a single-shifting field-motor substantially similar to that shown in case C may be employed, consisting of the coil 25, connected to the track-circuit and surrounding the core 24. The poles of the core are divided, and one section of one or both cores is surrounded by coils 35 and 36 in a closed circuit.

In lieu of changing the ratio of the transformer with the change of phase the ratio of the transformer is maintained constant, so that a change of the power factor will result when the reactance-coil 40 is connected in circuit as described—i. e., the active current is reduced. The contact-fingers 30 and 31 are connected to the disk 29 by a link which has a slotted connection with a weight 38, and the motor is so constructed that when the power factor of the current in the track-circuit is high—i. e., when the reactance 40 is cut out, the signal 4^a being clear—sufficient power will be developed to raise the weight and bring fingers 30 and 31 into contact with the plates 32 and 33, closing the circuits of signals 4 and 5, causing them to indicate "clear." When signal 4^a goes to "danger," the reactance will be connected in series in the track-current, thereby changing the normal phase relation of the voltage, with the current accompanied with a reduction of the power factor or active current, so that the motor can no longer sustain the weight, and the finger 31 will be shifted from contact with plate 33, thereby breaking the circuit of signal 5, which will then go to "caution."

I claim herein as my invention—

1. In a signaling apparatus for railways, the combination of a source of alternating currents, a track-circuit for said currents, two signaling mechanisms operative by said track-circuit currents, and means for changing the normal phase relation of the voltage with the current for effecting an operation of one of said mechanisms and not the other, substantially as set forth.

2. In a signaling apparatus for railways, the combination of a source of alternating currents, a track-circuit for said currents, a signaling mechanism operative by such track-circuit currents regardless of the phase relation of the voltage with the track-circuit current, a signal mechanism operative by such currents on a displacement of the phase relation of the voltage with the current and means for effecting such phase displacement, substantially as set forth.

3. In a signaling system, the combination of a home signal, a distant signal for the home signal, a track-circuit including a relay and source of alternating current for controlling each signal, and means for changing the phase of alternating current in one track-circuit by the other track-circ.

4. In a signaling system, the combination of a home and distant signal located at the same point, a single track-circuit and two relays for controlling the home and distant signals, a source of alternating current for said track-circuit to which one of said relays is responsive to operate one of said relays and not the other, and a second source of current for said track-circuit of different phase relation and to which the other of said relays is responsive.
5. In a signaling system, the combination

of a plurality of signals, a track-circuit and relay device for controlling both of said signals, and means for supplying alternating currents of different phase relation to said track-circuit to control the signals at different times.

In testimony whereof I have hereunto set my hand.

JACOB B. STRUBLE.
